TREATMENT OF HYDROCARBONS

Seymour W. Ferris, Aldan, Pa., assignor to The
Atlantic Refining Company, Philadelphia, Pa.,
a corporation of Pennsylvania

No Drawing. Application March 30, 1933,
Serial No. 663,552

9 Claims. (Cl. 196—13)

This invention relates to the art of hydrocarbon oil refining and has particular reference to the separation of hydrocarbon oils, especially crude petroleum or petroleum products, into fractions of different chemical composition while of approximately the same distillation range.

In accordance with my invention, hydrocarbon oils, particularly oils of substantial viscosity, are separated into various fractions by means of selective solvents, and more particularly by extraction with a solvent from the group comprising the mono- and poly-halogen substituted aliphatic oxy- and oxo-compounds, preferably the mono-compounds. My invention also contemplates mixtures of solvents containing substantial amounts of the compounds aforesaid. I mean by this classification to include particularly aliphatic organic compounds containing only carbon, hydrogen, oxygen and halogen in which the oxygen and halogen are each linked directly to carbon, such as the halogen derivatives of the aliphatic alcohols, ethers, aldehydes, ketones, acids and esters. Examples of this class of compounds are ethyl chloracetate, chloracetone, and dibrom propyl alcohol.

It is recognized in the art that mineral oils, such as petroleum, comprises essentially a mixture of hydrocarbons of various groups of homologous series of compounds, such for example, as paraffins of the general formula C_nH_{2n+2} , olefines of the general formula C_nH_{2n} , hydroaromatics and polymethylenes of the same empirical formula, and various other series of compounds of chain and/or ring structures in which the hydrogen to carbon ratio is less than in the foregoing series. A large number of individual compounds of each series and of differing boiling points are present in petroleum.

The various types of crude petroleum, which are generally classified into three groups, namely, paraffinic base, naphthenic or asphaltic base, and mixed base, contain the various series of hydrocarbons mentioned heretofore in different proportions. For example, in the paraffin base crude oils, such as those obtained from the oil fields of Pennsylvania, there is a relatively large proportion of hydrocarbons having a chain structure and a high hydrogen to carbon ratio, whereas in the naphthenic or asphaltic base crude oils, there is a relatively large proportion of hydrocarbons

having ring structures and a low hydrogen to carbon ratio. Mixed base crude oils, such as are obtained from the Mid-Continent oil fields, contain hydrocarbons in proportion intermediate these two extremes.

The variance in the proportion of the different series of hydrocarbons in paraffinic, naphthenic, and mixed base oils is evidenced by the physical properties of the various oils and particularly by the relationship of the specific gravity to the viscosity of one oil as compared with another. For example, an oil derived from a Pennsylvania crude and having a viscosity of 400 seconds Saybolt universal at 100° F., will show a specific gravity at 60° F. of about 0.878, whereas an oil of corresponding viscosity produced from a naphthenic crude, such as one from the Gulf Coast area, will show a specific gravity of about 0.933 at 60° F. The relationship between the viscosity and gravity indicates the degree of paraffinity or naphthenicity of the oil, and such relationship may be expressed by the viscosity-gravity constant as hereinafter described.

If a given crude petroleum be distilled into successive fractions and the specific gravities and viscosities of the several viscous fractions be determined, it will be found that they conform to the general relationship expressed by the formulae—

$$G = \frac{1.0752 - a}{10} \log (V - 38)$$

or

$$G = 0.24 + 0.755a + 0.022 \log (V' - 35.5)$$

in which "G" is the specific gravity at 60° F., "V" and "V'" are respectively Saybolt universal viscosities at 100° F. and 210° F., and "a" is a constant known as the viscosity-gravity constant. Viscous fractions from each of the different types of crude have different viscosity-gravity constants. While, in general, viscous fractions from a single crude have substantially the same viscosity-gravity constant, such constant is lower for fractions of the paraffinic crudes than is the constant for fractions of the naphthenic crudes. An article entitled "The viscosity-gravity constant of petroleum lubricating oils" by J. B. Hill and H. B. Coats, which will be found in vol. 20, page 641 et seq., I. E. C. for June 1928, explains the deter-

mination of such constant for several typical oils.

The viscosity-gravity constant is, therefore, an index of the paraffinicity of naphthenicity of viscous oils, since when a given crude is distilled, the fractions thereof collected, and the specific gravity and the viscosity of each of the viscous fractions determined, such specific gravities and viscosities substituted in the formula, and the viscosity-gravity constants of the fractions calculated, it will be found that such constants are substantially the same.

The viscosity-gravity constants of the viscous fractions of some of the typical crudes are as follows:

15	Milltown (Pennsylvania) -----	0.8067
	Burbank (Mid-Continent) -----	0.8367
	Gaudalupe (Gulf Coast) -----	0.8635
	Mirando (Gulf Coast) -----	0.9025

20 While the above figures indicate the viscosity-gravity constants of specific oils from several types of crudes, it is to be understood that for any particular type of crude such constant may be within a range between values above and below the constant of the typical crude given. For example, viscous oils resulting from the distillation of Mid-Continent crudes have viscosity-gravity constants ranging from about 0.835 to about 30 0.855, whereas the viscous fractions resulting from distillation of Pennsylvania type crudes range from about 0.805 to 0.828, and in most instances, are below 0.820. Oils are increasingly paraffinic as their viscosity-gravity constants decrease.

35 My invention is based upon the discovery that oils containing both the paraffinic and the naphthenic series of hydrocarbons may be fractionally extracted with halogen substituted aliphatic 40 oxy- and oxo-compounds. The various series of hydrocarbons possess a differential solubility in such a solvent, the naphthenic hydrocarbons being more soluble therein than the paraffinic hydrocarbons. By means of extraction with such 45 solvent, it is therefore possible to effect a partial separation of the naphthenic hydrocarbons from the paraffinic, and to obtain from an oil containing both classes of hydrocarbons, an oil fraction which is more paraffinic than the original oil and 50 one which is more naphthenic. By my invention, for example, it is possible to produce an oil of the quality normally obtained from Appalachian crudes, from crudes of the mixed base type from the Mid-Continent area, and, conversely, to 55 obtain oils from mixed base crudes such as are normally obtained from the naphthenic oils of the Gulf Coast area. In general, from oils from any source there may be obtained by my process, 60 oils which are respectively more paraffinic and naphthenic than the oils normally obtained from such source by distillation.

65 In accordance with my invention, I first mix the oil to be treated with a suitable proportion of the solvent at a temperature such that complete solution is effected and a homogeneous liquid obtained. I then cool the mixture to a temperature at which separation of the liquid into a two-layer system will take place. The upper layer 70 will contain a relatively small amount of solvent dissolved in the paraffinic portion of the oil while the lower layer will contain the more naphthenic oil dissolved in the solvent. Or, I may agitate the mixture of solvent and oil at temperatures at 75 which the liquids are only partially miscible, and

thereby effect solution of the naphthenic portion of the oil in the solvent. In either of the above procedures I may take advantage of the principles of countercurrent extraction. After extraction, I effect separation of the two layers which 5 form, by any suitable procedure, as for example, by decantation. I then remove from each of the separated layers, the portion of the solvent which each contains by suitable procedure, such as by vacuum distillation, thereby to obtain two oils of 10 similar distillation range but of different chemical composition and different physical properties. Before removing the solvent from the upper and more paraffinic layer, I may add a further quantity of solvent and repeat the extraction, thereby to remove additional naphthenic constituents from said layer.

15 My invention may be illustrated by the following specific examples:

20 100 parts of an untreated distillate obtained from a Gulf Coast crude oil and having a viscosity of 612 seconds Saybolt universal at 100° F., a specific gravity at 60° F. of 0.9303, and a viscosity-gravity constant of 0.874 was mixed with 300 parts of chlor-acetone and heated to slightly 25 above the temperature of complete miscibility, i. e., to approximately 85° C. The homogeneous liquid which resulted was cooled, with agitation, to 60° C. and allowed to settle, whereupon a two 30 layer system formed which consisted of an upper undissolved oil layer comprising 60.5 parts of the mixture and a lower layer of oil dissolved in chlor-acetone comprising 339.5 parts of the mixture. After separation the layers were each freed 35 of the solvent by vacuum distillation. The undissolved fraction yielded 2.9 parts of chlor-acetone and 57.6 parts of an oil having a viscosity of 459 seconds Saybolt universal at 100° F., a specific gravity of 0.936 and a viscosity-gravity constant of 0.843. The dissolved fraction yielded 40 297.1 parts of chlor-acetone and 42.4 parts of oil having a viscosity of 1542 seconds Saybolt universal at 100° F., a specific gravity of 0.9725 and a viscosity-gravity constant of 0.924.

45 When 100 parts of a Mid-Continent distillate having a viscosity of 154 seconds Saybolt universal at 210° F., a specific gravity of 0.9176 at 60° F. and a viscosity-gravity constant of 0.836 was extracted in the above described manner 50 with 300 parts of ethyl chloracetate, there resulted an undissolved oil fraction comprising 72% of the stock and having a viscosity of 141 seconds Saybolt universal at 210° F., a specific gravity of 0.9071 and a viscosity-gravity constant 55 of 0.824. The dissolved oil fraction comprising 28% of the original stock had a viscosity of 129 seconds Saybolt universal at 210° F., a specific gravity of 0.9446 and a viscosity-gravity constant of 0.875.

60 Table 1, given below, is a summary of extraction data comparing a group of aliphatic oxy- and oxo-solvents with their corresponding halogen derivatives. The data, in each case, represents a single extraction with the solvent indicated therein. It will be observed that each non-halogenated solvent was employed in the production of two undissolved oil fractions of different viscosity-gravity constants, by using two different ratios of volume of solvent to volume of 70 oil stock treated. Two extractions with the halogen derivative of each solvent were also made on the same oil stock as a basis for comparison of the halogenated and non-halogenated solvent. In the case of propyl alcohol and its brom-deriv- 75

ative only one extraction was made, the ratio of solvent to oil being 3:1.

Table I

Solvent	Sp. gr. solvent	Ratio vol. solvent to vol. of oil stock	Vis.-grav. constant of oil stock	Vis.-grav. constant of undissolved oil product	Vis.-grav. constant of dissolved oil	Vol. of undissolved oil prod. per vol. of solvent employed
Ethyl acetate	0.900	1	0.836	0.833	0.880	0.912
Ethyl chloracetate	1.159	1	0.826	0.821	0.884	0.869
Ethyl acetate		3	0.836	0.825	0.871	0.247
Ethyl chloracetate		3	0.836	0.824	0.875	0.240
Acetone	0.792	1	0.874	0.869	0.932	0.834
Chloracetone	1.162	1	0.874	0.858	0.950	0.787
Acetone		2	0.874	0.855	0.921	0.328
Chloracetone		3	0.874	0.843	0.924	0.192
Propyl alcohol	0.804	3	0.874	0.864	0.884	0.128
2, 3 dibrom propyl alcohol	2.083	3	0.874	0.836	0.941	0.190

The above table shows that halogenation increases the specific gravity of the aliphatic oxy- and oxo-compounds very substantially, which fact is important in that the specific gravity differential between solvent and oil is increased, thereby causing an increased rate of separation of the oil and solvent layers. It is desirable to have the specific gravity of the selective solvent as widely different from the specific gravity of the oil as possible, in order to bring about a rapid separation of the layers. The specific gravity of the solvent is of prime importance where the extraction process is to be carried on continuously, as the rate of thru-put of the oil, i. e., the capacity of the apparatus is determined by the readiness and rapidity of separation of the dissolved from the undissolved layer, which is a function of the gravity differential between dissolved and undissolved layers.

While halogenation, in general, improves the selectivity of the aliphatic solvents, the increase in specific gravity is perhaps of greater importance. The selective efficiency of the solvent may be of little practical importance if the specific gravity of such solvent does not differ sufficiently from that of the oil to allow a ready and rapid separation of the undissolved oil and solvent layers. The question of specific gravity differential between solvent and oil may well be the controlling factor as to the adaptability or preclusion of such solvent for practical use in selective extraction, particularly in a continuous extraction process.

The halogen derivatives of the aliphatic oxy- and oxo-compounds have, in general, a higher specific gravity than the corresponding non-halogenated solvents, and, as a class, are capable of producing, in a single extraction, a dissolved and an undissolved oil fraction having a greater viscosity-gravity constant differential than the non-halogenated solvents are capable of producing.

From the foregoing data it will be seen that by extraction of a mineral oil with a halogen derivative of an aliphatic oxy- or oxo-compound there may be obtained oil fractions which are respectively more paraffinic and more naphthenic than the original oil. By repetition of the extraction process or by a continuous countercurrent process, the undissolved oil fraction may be rendered increasingly paraffinic, as evidenced by a progressively decreasing viscosity-gravity constant.

In extracting oils containing appreciable quantities of wax, such oils may be dewaxed, for example, by cold settling or centrifuging prior to carrying out the extraction. My process is operable, however, in the absence of preliminary de-

waxing.

Herein, and in the appended claims, the term "viscous oil" is to be understood as comprehend-

ing an oil of substantial viscosity, i. e., of the order

of 50 seconds Saybolt universal at 100° F., or more.

What I claim is:

1. The process for separating mineral oils containing liquid paraffinic and naphthenic hydrocarbons into fractions which comprises bringing the oil into contact with a solvent from the group of halogenated oxygen containing aliphatic compound consisting of ethyl chloracetate, chloracetone, and dibrom propyl alcohol, thereby to effect solution of a portion of the oil richer in naphthenic hydrocarbons in the said solvent, separating the solution so formed from the remainder of the oil, and distilling the solvent from both of the portions of the oil, thereby to obtain fractions of the oil respectively richer in liquid paraffinic and naphthenic hydrocarbons.

2. In the art of refining mineral lubricating oil containing liquid paraffinic and naphthenic hydrocarbons, the step of fractionally extracting the oil with a solvent from the group of halogenated oxygen containing aliphatic compounds consisting of ethyl chloracetate, chloracetone, and dibrom propyl alcohol, to effect a separation of fractions respectively richer in liquid paraffinic and naphthenic compounds.

3. In the art of refining mineral oils, the process which comprises adding a solvent from the group of halogenated oxygen-containing aliphatic compounds consisting of ethyl chloracetate, chloracetone and dibrom propyl alcohol to an oil containing liquid paraffinic and naphthenic hydrocarbons, heating the mixture to such temperature as to effect solution, cooling the solution to form a two-layer system, separating the upper layer from the lower layer and removing the solvent from at least one of said layers.

4. In the art of refining mineral oils, the process which comprises adding a solvent from the group of halogenated oxygen-containing aliphatic compounds consisting of ethyl chloracetate, chloracetone and dibrom propyl alcohol to an oil containing liquid paraffinic and naphthenic hydrocarbons, heating the mixture to such temperature as to effect solution, cooling the solution to form a two layer system, removing the lower layer, and similarly re-treating the upper layer with said solvent.

5. The process of treating a viscous fraction of a crude oil of one type containing liquid paraffinic and naphthenic hydrocarbons to procure a fraction having the quality of a corresponding fraction of a crude oil of different type having a greater content of liquid paraffinic hydrocarbons, which comprises extracting the viscous fraction with a solvent from the group of halogenated oxygen-containing aliphatic compounds consist-

ing of ethyl chloracetate, chloracetone and dibrom propyl alcohol, and separating the oil so treated into portions respectively richer in liquid paraffinic and naphthenic hydrocarbons.

- 5 6. In the art of refining mineral oils, the process which comprises bringing a solvent from the group of halogenated oxygen-containing aliphatic compounds consisting of ethyl chloracetate, chloracetone and dibrom propyl alcohol, into intimate contact with a viscous hydrocarbon oil of a quality other than that of a Pennsylvania type viscous oil, and containing paraffinic and naphthenic components, thereby to dissolve from the oil substantial amounts of its naphthenic components, thereafter removing the solvent and oil dissolved therein from that portion of the oil which remains undissolved, thereby to produce an oil such as is normally obtained from Pennsylvania type crude by distillation.
- 10 7. In the art of refining mineral oils, the process which comprises bringing a mineral oil containing paraffinic and naphthenic hydrocarbons into contact with a solvent from the group of

halogenated oxygen-containing aliphatic compounds consisting of ethyl chloracetate, chloracetone and dibrom propyl alcohol, thereby to effect solution of a portion richer in naphthenic hydrocarbons in the solvent, separating the solution so formed from the remainder of the oil, and re-treating the oil remaining with additional amounts of said solvent.

8. The process of decreasing the viscosity-gravity constant of a viscous mineral oil which comprises extracting the oil with a solvent from the group of halogenated oxygen-containing aliphatic compounds consisting of ethyl chloracetate, chloracetone and dibrom propyl alcohol.

9. The process of treating a viscous hydrocarbon oil having a viscosity-gravity constant between substantially 0.835 and 0.875 to reduce the viscosity-gravity constant by at least 0.015, which comprises extracting said viscous oil with a solvent from the group of halogenated oxygen-containing compounds consisting of ethyl chloracetate, chloracetone and dibrom propyl alcohol.

SEYMOUR W. FERRIS.
